(57) **CLAIM**

The ornamental design for an aquarium cover, as shown and described.

DESCRIPTION

FIG. 1 is an environmental perspective view of an aquarium cover showing our new design;

FIG. 2 is a front elevational view thereof;

FIG. 3 is a rear elevational view thereof;

FIG. 4 is a right side elevational view with the left side being a mirror image thereof;

FIG. 5 is a top view thereof; and,

FIG. 6 is a bottom view thereof.

The broken line showing of the aquarium, fish, and plants in FIG. 1 is for illustrative purposes only and forms no part of the claimed design.
